Primary Examiner — Mary Ann Calabrese*Assistant Examiner* — Katelin G Kloberg(74) *Attorney, Agent, or Firm* — Nitin Kaushik(57) **CLAIM**

The ornamental design for a folding bed, as shown and described.

DESCRIPTION

FIG. 1 is a front perspective view of a folding bed, showing my new design in a folded configuration;

FIG. 2 is a rear perspective view thereof;

FIG. 3 is a front view thereof;

FIG. 4 is a rear view thereof;

FIG. 5 is a left side view thereof;

FIG. 6 is a right side view thereof;

FIG. 7 is a top view thereof;

FIG. 8 is a bottom view thereof; and,

FIG. 9 is a front perspective view of the folding bed, shown in an open configuration.

The broken lines in the drawings illustrate the portions of the folding bed, which form no part of the claimed design.

1 Claim, 9 Drawing Sheets(56)
